(57) CLAIM

The ornamental design for a deskspool, as shown and described.

DESCRIPTION

FIG. 1 is a front perspective view of a powerspool, according to a design of the present invention.

FIG. 2 is a front view of the powerspool of FIG. 1.

FIG. 3 is a rear view of the powerspool of FIG. 1.

FIG. 4 is a right side view of the powerspool of FIG. 1.

FIG. 5 is a left side view of the powerspool of FIG. 1.

FIG. 6 is a top view of the powerspool of FIG. 1.

FIG. 7 is a bottom view of the powerspool of FIG. 1; and, FIG. 8 is another front perspective view thereof with broken lines used to indicate an alternate environment.

The broken line showing of portions of the powerspool is for illustrative purposes only and forms no part of the claimed design.
